UNITED STATES PATENT OFFICE

LOUIS T. HERRMANN, OF SAN DIEGO, CALIFORNIA

TYPEWRITER DESK

Application filed October 7, 1924. Serial No. 742,180.

My invention relates to desks for typewriters or other similar machines, particularly to such a desk in which the typewriter or other machine is supported on a non-tiltable platform or table, and the objects of my invention are, first, to provide a desk of this class which is provided in and below its main top member with a passage extending substantially from front to rear, whereby a typewriter or other machine, positioned at the rear of the desk within and below a superstructure when not in use, may be easily pulled forwardly to the position desired for use; second, to provide a desk of this class having a stationary machine-supporting panel or member extending the full length and width of the desk to provide a rigid construction for a desk of this class having its main top member partially cut away crosswise, as in the conventional construction; third, to provide a typewriter desk having a typewriter-supporting panel extending the whole length and width of the desk, providing a rigid structure therefor and permitting 25 a single or double typewriter desk to be made with four legs only; fourth, to provide a superstructure for a desk of this class into which the removable portions or panels of the top and front side members of the desk 30 may be positioned when the typewriter or other machine is adapted to be pulled outwardly for use; fifth, to provide a novel means, in a desk of this class, for limiting the outward movement of the shiftable machine- 35 supporting platform and a novel means for varying the limit of said movement; sixth, to provide a novel means for retaining said shiftable machine-supporting platform in position after the same is pulled outwardly; 40 seventh, to provide a novel and dust-proof desk for typewriters and other similar machines; eighth, to provide a novel means for locking the removable panels of the top and front side members in position when the desk 45 is closed; ninth, to provide a novelly constructed and operated mechanism for limiting and fixing the outward position of a shiftable machine-supporting platform; and, tenth, to provide a desk for typewriters and 50 other similar machines which is simple and

economical of construction, durable, and which will not readily deteriorate or get out of order.

With these and other objects in view as will appear hereinafter, my invention consists of certain novel features of construction, combination and arrangement of parts and portions, as will be hereinafter described in detail and particularly set forth in the appended claims, reference being had to the accompanying drawings and to the characters of reference thereon, which form a part of this application, in which:

Figure 1 is a front elevational view of my desk with certain parts and portions thereof broken away and in sections to facilitate the illustration; Figure 2 is a plan view thereof, also showing certain parts and portions broken away and in sections to facilitate the illustration; Figure 3 is a sectional elevational view thereof taken thru 3-3 of Figure 1; Figure 4 is a fragmentary, sectional view in plan taken thru 4-4 of Figure 1; Figure 5 is an enlarged fragmentary plan view showing the relation between the typewriter-supporting platform, the roller means and the platform limiting and retaining means; Figure 6 is a sectional, elevational view thereof taken thru 6-6 of Figure 5; and Figure 7 is another sectional, elevational view thereof taken thru 7-7 of Figure 5.

Like characters of reference refer to similar parts and portions throughout the several views of the drawings.

My desk consists essentially of leg members 1, a top member 2, supported at the upper ends of said leg members and provided intermediate its ends and at its front portion with a cut away portion 2^a, a rigid stationary typewriter-supporting panel 3, positioned below the top member 2 and extending between said leg members and supported thereby, a superstructure 4, positioned at the rear portion of the top side of the top member 2 and provided at its front side intermediate its ends with a large opening 4^a, a cover member 5 for said opening, a top panel 6 for the cut away portion in said top member, a front side panel 7 for the opening in the front side of the desk, and a shiftable 100

typewriter-supporting platform 8 reciprocally mounted on the supporting panel 3 within the passage provided in the desk. When embodying my invention in a single type typewriter desk, that is, in one having drawers on one side only, one of the drawers 9 is positioned at one side between the top member 2 and the member 3, and the other drawers are suspended from the member 3 and one of the leg members as shown best in Figure 1.

At the sides of the top member 2 forming the opening 2^a therein are provided ledges 2^b upon which are adapted to be supported corresponding off-set portions at the side edges of the top panel 6. The front ends of the ledges 2^b are cut away as shown best by dotted lines in Figure 2, to receive the downwardly extending apron 6^a at the front edge of the top panel 6. Between the supporting ledges 2^b and the sides of the top member 2 forming the opening therein are provided grooves 2^c for catching dust. On the under sides of the off-set portions at the side edges of the top panel 6 is secured felt 11 for sealing the typewriter compartment in the desk. At the side edges of the under sides of the panel member 6 are secured top panel retaining members 12 for retaining the top panel 6 in position. These members 12 are adapted to be retained in longitudinal grooves 2^d at the sides of the ledges 2^b.

The ends of the removable front side panel 7 are provided with vertical grooves 7^a which are adapted to receive corresponding tenons 13^a at the edges of the front side members 13. The front edge of the panel 3 is rabbeted, as indicated by 3^a in Figure 3, to receive the lower edge of the removable front side panel 7. The joints between the panel 3 and top panel 6 and the removable front side panel 7 are also sealed by felt 11, as indicated in Figure 3 of the drawings. The cover member or door 5, adapted to enclose the opening 4^a at the front side of the superstructure 4, is provided at its sides near its upper edge with pins 5^a which are hinged at the one end of and adapted to slide inwardly in grooves 4^b at the upper portion of the sides of the compartment in the superstructure, as shown best in Figure 3, to permit the door 5 to be raised about its pivotal mounting and partially inserted edgewise at the upper portion of the superstructure, as shown in Figure 1. This door when inserted edgewise into the superstructure rests on a horizontal partition 14. At the inner edge of the top panel 6 is provided an upwardly extending ledge 6^b which is adapted to be engaged by the lower edge of the door 5, when the same is closed. When this door 5 is locked by means of a lock or bolt means, as indicated by 15 in Figures 1 and 2, when in a closed position, the panels 6 and 7 cannot be removed. The inner side of the door 5 is also preferably covered near its

edges with felt 11 to seal the interior of the superstructure from dust.

In the superstructure 4, below the partition 14, extending horizontally therein, is provided another horizontal partition 16, spaced from the partition 14. In this space between the partitions 14 and 16 are adapted to be positioned the top panel 6 and the front side panel 7, when the desk is opened and in use, as shown by dotted lines in Figures 1 and 3. The panels 6 and 7 are separated in said space by a vertical partition 17.

At the lower side portions of the passage, formed within the desk by the cut away portions in the table top member 2 and the front side member 13, are positioned guide members 18 which may be secured to the stationary typewriter-supporting panel 3. Between these guide members 18 is reciprocally mounted the shiftable typewriter platform 8 which is provided with a plurality of rollers 19.

These rollers 19 consist of frames 19^a inserted and secured into the platform 8, and roller members 19^b revolvably mounted therein in such a manner as to raise the platform 8 only a slight distance from the stationary typewriter-supporting panel 3, as shown best in Figure 6.

The forwardly positioned rollers 19 are provided with frames having upwardly extending portions 19^c at their outer edges. These portions 19^c are adapted to engage inwardly extending lugs 20^a and 20^b, respectively at the rear and front ends of the typewriter platform stop and retaining members 20 reciprocally mounted at the upper

sides of the guide members 18 by means of the screws 21 at their front ends and thumb screws 22 near their rear ends. At the top sides of the guide members 18 are provided a plurality of tapped holes 18^a into which the thumb screws 22 are adapted to be screwed for variously limiting the outward movement of the typewriter platform 8. Thus it will be seen that when the platform 8 is pulled outwardly the upwardly extending portions 19^c of the forwardly positioned roller frames will engage the inwardly extending lugs 20^b of the members 20, forcing the same outwardly to the position shown by dotted lines, the outward positions of the members 20 depending upon the position of the thumb screws 22 relatively to the guide members 18.

The lugs 20^a of the members 20 are adapted to be engaged by the portions 19^c when the platform 8 is pushed inwardly, thus forcing the members 20 inwardly. It will be noted that the members 20 extend inwardly over the platform 8 so that said members also perform the function of holding the platform 8 downwardly against the stationary supporting panel 3.

In the upwardly extending portions 19^c of the forwardly positioned roller frames 19^a are revolvably mounted spindles 23 which are provided with eccentric discs 24 as shown best in Figures 6 and 7. These eccentric discs 24

are rotatably mounted in annular portions 25^a of the platform raising plungers 25 which are reciprocally mounted in the roller frames and also thru the typewriter-supporting platform. 8. The spindles 23 are provided with levers 26 which are adapted to raise and lower the plungers 25 depending upon the position thereof relatively to the platform, the position of the lever 26 in Figure 7 of the drawings showing the plunger 25 forced downwardly for raising the front rollers 19 of the platform 8 from the supporting panel 3. At both sides of the outer or front portions of the stationary member 3 are provided plates 27 having a plurality of spaced counter-sunk holes 27^a which are adapted to receive the ends of the plungers 25 as shown in Figure 7. The spacing between the holes 27^a in the plates 27 is preferably less than the spacing of the tapped holes 18^a in the guide members 18 so as to provide a greater variation of adjustment for the position of the typewriter. When the levers 26 are rotated about the supports 19^c to the position shown in Figure 4, 25 the plungers 25 are raised from the plates 27 permitting the front rollers to engage the panel 3, thus permitting the platform 8 to be shifted backwardly.

It is obvious from this construction, as illustrated in the drawings and disclosed in the foregoing specification, that there is provided a desk for typewriters or other similar machines as aimed at and set forth in the objects of the invention, and though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. In a desk, a platform supporting panel member, a shiftable platform reciprocally mounted on said panel member, an adjustable and shiftable stop means mounted on said panel member for retaining said platform thereagainst and for limiting the outward position of said platform, and a lever means mounted on said platform and engageable with said panel member for raising the forward end of said platform from said panel member when the same is shifted to any desired outward position.

2. In a desk structure, a panel member, a platform reciprocally mounted above said panel member, guide means for said platform, and an adjustable and shiftable slide mounted on said guide means and overlapping one side of said platform, means for releasably securing said slide to said guide means, said slide retaining said platform in a downward

position and forming stop means for limiting the outward position thereof, said slide being shiftable independently of or by said platform.

3. In a desk structure, a panel member, a platform reciprocally mounted above said panel member, guide means for said platform, an adjustable and shiftable means mounted on said guide means overlapping the side of said platform for retaining said platform in a downward position and forming stop means for limiting the outward position thereof, and a lever and eccentric means for raising the forward end of said platform when the same is shifted to its outward position.

In testimony whereof, I have hereunto set my hand at San Diego, California, this 29th day of September, 1924.

LOUIS T. HERRMANN.
